UNITED STATES PATENT OFFICE

DUDLEY D. LEVY, OF NEW YORK, N. Y., ASSIGNOR TO DUDLEY RESEARCH CORPORATION,
OF NEW YORK, N. Y., A CORPORATION OF NEW YORK

MACHINE FOR AFFIXING IDENTIFICATION SEALS OR TAGS

Application filed March 12, 1929. Serial No. 346,464.

This invention relates to a machine for affixing identification seals or tags to various commodities or articles such as furs, skins, rugs, leather, aluminum, oil-cloth, ⁵ tiles, paper and textile goods, and the like.

The object of the invention includes the production of a machine for rapidly and securely fastening on the goods in question the manufacturer's identification seal or tag in ¹⁰ such a way that the securing elements of the seal or tag are hidden from view and that the seal or tag cannot be removed or replaced without detection.

Another object resides in the provision of ¹⁵ means whereby the seal or tag members are fed into position from opposite directions and are placed upon the commodity or article to be tagged or sealed by a single operation of the machine.

²⁰ Another object of the invention includes the provision of a comparatively simple and inexpensive machine by which the above object is accomplished and which will feed the seal or tag members into position from either ²⁵ strips of seal or tag members, or as individual seal or tag members, and place the same in the path of the sealing element whereby the two members of the seal are brought together on opposite surfaces of the skin or commodity ³⁰ to be sealed and then fastened thereto.

Other objects will appear hereinafter and I obtain these objects by the construction shown in the accompanying drawings, in which

³⁵ Figure 1 is a front view elevation of a machine suited for carrying out my purpose;

Fig. 2 is an elevation viewed from the right-hand side of Fig. 1;

Fig. 3 is an elevation viewed from the left-hand side of Fig. 1;

Fig. 4 is a top plan view thereof;

Fig. 5 is a view on the line 5—5 of Fig. 3 showing the tag or seal chutes in relation to the sealing members;

⁴⁵ Fig. 6 is a view from the left-hand side of Fig. 5 with the chute covers removed;

Fig. 7 is an enlarged detail of a portion of the construction shown in Fig. 5, showing the upper sealing member in position upon the material and the lower sealing member

ready to be moved up onto the material to be tagged;

Fig. 8 is a view of the lower portion of the upper tag chute and related parts;

Fig. 9 is a sectional view thereof showing the tag placed in the position which it takes before it is moved down upon the material to be sealed or tagged; ⁵⁵

Fig. 10 is a front view of the lower portion of the chute shown in Fig. 9; ⁶⁰

Fig. 11 is a view taken on line 11—11 extended on Fig. 3 to show the relation of the links and the movable sealing member but omitting the upper chute;

Fig. 12 is a plan and side elevational view ⁶⁵ of a strip of tag or sealing members suitable for use in my apparatus.

Like numerals of reference will refer to similar parts throughout the several views wherever they occur.

It has been found, in connection with various commodities such as those named in the opening paragraph, that the seal or identification tags are not always securely fastened to prevent being removed accidentally or intentionally. I have discovered and invented seal members which will prevent accidental or intentional removal of seal members from the goods or commodities identified by such members and have devised a machine for effectively placing the said seal members onto the commodities to be tagged or sealed. The use of the seal members is very extensive and these seal members are proposed to be affixed quickly and securely by my machine which I have invented for this purpose. The essential elements of the machine include means for supporting and feeding tag members from opposite directions in position so that these may be applied to the goods on the opposite surfaces thereof and be secured thereto in such a way as to be not removed or replaced without indicating that the seal has been broken. The sealing is accomplished by two movable jaws which are so arranged as to move onto the goods in successive stages. That is, the upper jaw moves down and places the sealing member onto the goods first, then the lower jaw moves upward and places the lower sealing member onto the goods and the

⁷⁵

¹⁰⁰

two sealing elements are then pressed together so that their interlocking tines engage the goods underneath the tags themselves so as to be completely hidden from view. The tags may be made up in strips from suitable metal such as steel, or the like.

One form of apparatus suitable for carrying out my invention comprises a base plate 20 of suitable dimensions having an upper reinforcing plate 21 and a lower re-enforcing plate 22 through which are suitable apertures for holding and securing sleeves 23. In this particular instance there are two sleeves side by side to movably receive two parallel guide bars 24. On the upper end of the guide bars 24 there is secured a head or pivot lever member 25. On the lower end of said guide bars there is fastened and secured the lower anvil jaw 26 having a sealing head 26'. On the upper portion of the guide bars above the sleeves 23 there is movably held the upper anvil jaw 27 having a sealing head 27'.

An operating lever 28 is pivoted at 29 in the head or pivot lever member 25. A pair of links 33 are secured to the end of the lever at 32, and the lower end of these links is pivotally united at 34 onto the upper anvil jaw 27. The apparatus is operated by suitable means such as a foot lever 31 and connecting link 30 in the manner readily understood.

The upper anvil jaw carries fastened thereon the upper tag chute 35, and the lower anvil jaw has secured thereto the lower tag chute 36. This chute 36 is an open trough as is best shown in Fig. 3 and has a chute cover 36'. This chute and cover move up and down as the lower jaw is moved up and down in a manner to be explained more fully below.

The upper tag chute is also an open trough 40 and is covered by a chute cover 37. This member carries secured thereon a spring 38 for holding the tag or tag strips in position. Within the upper tag chute there is provided an inner tag advancing or positioning chute 39 having a spring 38' for advancing the tags 40 into position as will be more fully explained below. In the lower portion of the tag advancing and positioning chute 39 there is provided a tag bending or positioning fork 41 which is fixed on the end of the bell crank 42 so as to rock thereon and bend the tag 40 into a fixing position in the path of the descending anvil jaw head 27'. The other end of bell crank 42 engages a toggle link 43 which is secured by bracket 44 onto the base-plate 20. From this construction it will be seen that whenever the anvil jaw 27 moves upward it will carry with it the chute 36, cover 37 and the tag advancing chute 39, together with the springs 38 and 38'. It will be noted that the slot in link 43 is of such length as will engage the end of bell crank lever 42 and hold the same from advancing in a certain position thereby pulling down the tag advancing chute 39 and rocking the

tag positioning fork 41 so as to place a tag 40 into proper position on the head of the anvil jaw. This action takes place during the upward movement of the anvil jaw 27 so that the tag is in position to be applied when the jaw 27 is moved downward. A presser plate or foot 45 on the lower end of the tag advancing chute 39 is fastened thereto and this presser foot descends upon the material 46 so as to hold the same in position in the manner shown in Fig. 7, during the time when the corresponding lower anvil jaw moves the lower tag onto the material from the opposite side.

For the purpose of feeding and providing tags for the lower side of the material, the lower tag chute 36 is provided, as described above. This member is fastened onto the lower anvil jaw in the manner shown in Figs. 5 and 7. This member, therefore, moves down and up with the lower anvil jaw.

Within this member there is provided the lower tag positioning chute 49 which is fastened onto the base-plate 20 by suitable means, such as rivets 47. The construction 90 of this member is substantially a duplicate of the upper tag chute placing member 39, described above. In this instance, however, it is secured to the base-plate and is not movable.

A tag placing fork 51 secured to and operated by bell crank 52 for bending or positioning the tags 40 into operative position in the manner shown in Fig. 7 is provided. A toggle link 53 provided with a slot engages the opposite end of bell crank 52. The upper end of this link is pivotally fastened by bracket 54 onto the upper anvil jaw 27 whereby said link is moved up and down. In its upward movement, however, when the end of the slot is reached bell crank 52 is rocked so

as to bend tag 40 into the position shown in Figure 1 in which position it is retained as the lower jaw is moved upwards to carry with it said tag and place the same on the under-surface of the goods 46 where it is secured when the jaws are pressed together. This operation occurs consecutively. That is, the upper member moves down into position first, and then the lower member is moved into its position thereafter, thus having the advantage of holding the goods in firm position upon the plate 20. It will be noted that a knife 60 shears the lower tag from its strip and the edge of the presser foot 45 similarly shears the upper tag from its strip, as is shown in Fig. 7. Spring 48 is secured to member 49 to hold this tag into position, and spring 50 serves as a feeding or advancing member when the chute carrying said spring is moved up and down. A 110 return spring 55 on bracket 58 aids in returning the lower anvil jaw into open position. The lower anvil jaw is moved up and down on the guide stem 56, as is best shown in Fig.

2. The upper end 57 of this stem serves as a 130

stop and fulcrum member for the upper jaw when it is brought down into closed position.

From the description thus far given it will be apparent that a succession of seal members, either in strips or otherwise, is constantly supplied and fed into position in front of the jaw members so as to be brought down into sealing position when the jaw members close. This operation is accomplished by the 10 movement of the operating lever in the direction shown by the arrow on Fig. 2, thereby causing the upper anvil jaw and associated parts to descend onto the material in the manner shown in Fig. 7. During the descent the 15 lever is fulcrumed at 29. The moment, however, that jaw member 27 engages stop member 37 the continuing motion of lever 28 will pull the guide bars 24 upwards and with it move the lower jaw and associated parts in 20 upward direction so as to close onto the material in the manner shown in Figs. 7, 5 and 3, respectively, in succession. When now the jaws are to be released member 28 is rocked in 25 the opposite direction. This returns the lower jaw and then carries up the upper jaw member and associated parts to such an extent as will be permitted by the movement of the lever. When the end of bell crank 42, which engages with the slot in link 43, reaches 30 its end the tag strip in the advancing chute 39 is pulled downward into advance position carrying with it a new tag. As the receding motion continues the bell crank lever will be rocked to bend tag 40 into position in the 35 manner shown in Fig. 9. During this time the lower lever jaw and chute will have receded into its normal position and a new tag is retained in advance position and bent by reason of bell crank lever 52 being rocked in 40 the manner described above, thus bringing a lower tag into the path of the lower jaw head for the purpose stated.

The tags themselves may assume various shapes, such as square, or other forms, and in the preferred form used in connection with this apparatus they are retained in strips with under cuts 61 and tines 62. These tines are stamped out of the metal as shown. A boss 63 serves to engage the end of the tine and 50 turn these under so as to firmly rivet the same onto the material.

It will be obvious to those versed in the art that various changes in the mechanism will suggest themselves and I do not, by the specific description just given, intend to limit myself to the exact structure excepting as herein claimed.

What I claim, therefore, as new and useful is:

60 1. In a seal and tag affixing machine, a base-plate having sleeves therethrough, a guide bar movably held in each of said sleeves to extend above and below said base-plate, an anvil jaw secured to said bars beneath said 65 base-plate, a second anvil jaw slidably mounted on said bars above said base-plate, a head or pivot lever member to which said bars are fastened, an operating lever pivotally mounted in said head, means for moving in succession said upper and said lower anvil jaws respectively towards said base-plate and 70 then away again, and means for placing a seal member in the path of said upper and lower anvil head. 75

2. In a seal and tag affixing machine, a base-plate having sleeves therethrough, a guide bar movably held in each of said sleeves to extend above and below said base-plate, an anvil jaw secured to said bars beneath said base-plate, a second anvil jaw slidably mounted on said bars above said base-plate, a head or pivot lever member to which said bars are fastened, an operating lever pivotally mounted in said head, means for moving in succession said upper and said lower anvil jaws respectively towards said base-plate and 75 then away again, and means for placing a seal member in the path of said upper and lower anvil head. 80

2. In a seal and tag affixing machine, a base-plate having sleeves therethrough, a guide bar movably held in each of said sleeves to extend above and below said base-plate, an anvil jaw secured to said bars beneath said base-plate, a second anvil jaw slidably mounted on said bars above said base-plate, a head or pivot lever member to which said bars are fastened, an operating lever pivotally mounted in said head, means for moving in succession said upper and said lower anvil jaws respectively onto a commodity to which the seal or tag members are affixed from opposite sides, and means for positioning new seal members as the jaw members are opened. 85

3. In a seal and tag affixing machine, a base-plate having a pair of sleeves, guide bars movably mounted in said sleeves, an anvil jaw slidably mounted on said guide bars, a second anvil jaw fastened to said guide bars, a tag supplying means associated with said anvil jaws, and means for successively bringing the head of each jaw respectively into tag affixing position onto the base-plate. 90

4. In a seal and tag affixing machine, a base-plate having a pair of sleeves, guide bars movably mounted in said sleeves, an anvil jaw slidably mounted on said guide bars, a second anvil jaw fastened to said guide bars, tag supplying means associated with said anvil jaws, means for successively withdrawing said anvil jaws from the sealing position, and means for injecting new seal members into the path of each anvil head. 100

5. In a seal and tag affixing machine, the combination of means for advancing seal members toward each other onto opposite sides of a commodity to be sealed or tagged, means for positioning one of said seal members onto said commodity in advance of the other member, means for pressing said seal members together on the commodity, and means for severing said pressed seal members from their successive seal members as the seal members are affixed. 110

6. In a seal and tag affixing machine, the combination of means for guiding seal members from opposite directions towards each other onto opposite sides of a commodity to be sealed or tagged, an upper jaw member and a lower jaw member mounted to move towards each other, means to position said members successively onto the opposite surfaces of said commodity, means for moving each of said jaws away from one side of the 125 130

5 seal and then from the other, means for interposing a new seal member into the path of each of said jaw members, and means co-operating with each jaw member for severing the seal member from its successive seal member when said new seal member is affixed.

7. In a seal and tag affixing machine, the combination of means for guiding seal members towards each other and placing said 10 members face to face on opposite sides of a commodity to be sealed or tagged, a pair of jaw members mounted to move towards each other in stages, means to position said members on the opposite surfaces of said commodity, means to interpose a new seal member into the path of each jaw member, means to bring one of the jaw members into sealing position in advance of its companion, and means cooperating with each jaw member 15 for severing the seal member from its successive seal member when said new seal member is affixed.

8. In a seal and tag affixing machine, the combination of means for guiding and means 20 for advancing strips of seal members towards each other onto opposite sides of a commodity to be sealed, means for placing said seal members face to face on opposite sides of said commodity, a pair of jaws mounted to move 25 towards each other and position said seal members on the opposite surfaces of said commodity to form a seal thereon, means for releasing said jaws and move the same away from said seal, and means for bringing new 30 seal members into the path of said jaws.

In testimony whereof I have hereunto set my hand on this 9th-day of March A. D., 1929.

DUDLEY D. LEVY.
